Primary Examiner — Paula Allen Greene*(74) Attorney, Agent, or Firm* — Lynne M. Blank, Esq.(57) **CLAIM**

I claim the ornamental design for a grave marker medallion, as shown and described.

DESCRIPTION

Reference is made to commonly assigned, co-pending U.S. patent application: Ser. No. 29/583,460 by Robert G. Capurso, entitled "Grave Marker Medallion", filed on even date herewith.

FIG. 1 is a front view showing a new design for a grave marker medallion.

FIG. 2 is a back view of the grave marker medallion, which is opposite the view of FIG. 1.

FIG. 3 is an exploded view showing the grave marker medallion of FIG. 1. The attachment of the rank/office plaque is illustrated.

FIG. 4 is a first side view of the grave marker medallion of FIG. 1.

FIG. 5 is the second side view of the grave marker medallion, which is opposite the view of FIG. 4.

FIG. 6 is a top or plan view looking down of the grave marker medallion of FIG. 1; and,

FIG. 7 is a bottom view looking up of the grave marker medallion of FIG. 1.

The features shown in broken lines and portions contained within broken lines, for example, the push pins, depict portions of the grave marker medallion that form no part of the claimed design, and are not claimed.

The insignia on the medallion forming part of the design is the property of the Boy Scouts of America, 1325 West Walnut Hill Lane, Irving, Tex. 75015
